CLAIM

The ornamental design for a fishing line rod bobber, as shown and described.

DESCRIPTION

FIG. 1 is a perspective view of a fishing line rod bobber in full lines with a fishing rod and line shown in broken lines representing environmental association matter being for illustrative purposes only and forming no part of the claimed invention.

FIG. 2 is a perspective view of the fishing line rod bobber. FIG. 3 is a front elevational view thereof, the rear elevational view being a mirror image of the front view.

FIG. 4 is a left side elevational view thereof.

FIG. 5 is a right side elevational view thereof.

FIG. 6 is a bottom plan view of the fishing line rod bobber; and,

FIG. 7 is a top plan view thereof.
